UNITED STATES PATENT OFFICE

JACOB RICHARD FRANCIS, OF FLINT, MICHIGAN

CARBURETOR

Application filed December 19, 1921. Serial No. 523,328.

This invention relates to certain new and useful improvements in carburetors and more particularly to means for retarding the opening movement of the suction controlled air valve, such as used in connection with Marvel carburetors and is an improvement on the construction of carburetor shown in my application filed June 15, 1921, Serial No. 477,768, the object being to provide an air screw dash pot, by means of which the movement of the air valve will be slightly retarded in opening so as to increase the efficiency of the internal combustion engine when the carburetor is installed thereon by obtaining what is known as a quick "pick-up".

Another and further object of my invention is to provide a carburetor in which the air valve is retarded by a combined fluid and spring dash pot whereby a fine adjustment can be obtained and the movement of the air valve controlled to a nicety so as to obtain the desired results.

A still further object of the invention is to provide a construction which is capable of being used in connection with various forms of carburetors where a movable air valve is employed.

Another object of the invention is to provide a carburetor having a pivoted air valve to which is connected a pivoted rod which in turn is connected to a piston mounted in a hollow screw, said piston having a vent in order to form a dash pot whereby the movement of the valve is retarded.

Other and further objects and advantages of the invention will be hereinafter set forth and the novel features thereof defined by the appended claims.

In the drawing I have shown a side elevation of an ordinary Marvel carburetor, partly in section, comprising a shell 1 having a mixing chamber 2, air inlet 3, high speed nozzle 4, and insert 5 provided with a low speed nozzle as now generally used in this construction of carburetor. Pivottally mounted on the insert 5 is an air or suction controlled valve 6 which extends up above the high speed nozzle 4 and is adapted to be normally held against the wall of the mixing chamber.

The above description is given so that the

operation of my improved construction of air screw and dash pot can be clearly understood when applied to this type of carburetor, but it is, of course, understood that I do not wish to limit myself to the use of any particular type of carburetor as my improved construction of air screw and dash pot is capable of being used on various constructions of carburetors where a movable air valve is employed.

The mixing chamber is provided with a threaded bore 7 in the wall thereof, in which works the threaded portion 8 of a tubular adjusting screw 9 which is provided with a fluted outer end 10 against which a ratchet spring 11 bears for holding the adjusting screw in its adjusted position within the threaded bore.

Slidably mounted within the tubular adjusting screw 9 is a piston 12, the head of which is apertured at 13, said piston sliding freely within the tubular adjusting screw and is normally held in extended position by a spring 14 so that the inward movement of the piston within the tubular adjusting screw is resisted by the tension of the spring and as the piston moves within the tubular screw the air within the same is forced through the vent or passage 13 which forms a dash pot arrangement so as to resist the movement of the piston within the tubular screw.

Pivottally mounted in the outer end of the piston at 15 is a rod 16, the other end of which is pivottally mounted in a bifurcated stem 17 extending outwardly from the valve 6 and it will be seen that by this construction the rod is pivottally connected at one end to the valve and at its opposite end to the piston 12 in order to allow the piston 12 to move freely within the tubular adjusting screw.

In the construction of carburetor as herein shown, the vacuum produced within the mixing chamber extends within the cylinder formed by the tubular valve so that a certain amount of fuel such as gasoline is drawn within the shell so as to keep the piston and spring thoroughly lubricated.

In my former application the rod was connected to the spring so that the opening

movement of the air valve was resisted by the spring alone while in this application, the piston and bore of the tubular plug forms a fluid dash pot by means of which the movement of the piston is retarded so that the opening movement of the air valve is retarded and by the particular manner of connecting the rod to the piston and air valve a connection is formed which allows the piston to move freely within the tubular adjusting screw.

From the foregoing description it will be seen that I have provided an improved construction of air screw and dash pot for a suction controlled valve used in connection with a carburetor whereby I am able to control the movement of the air valve in such a manner that the valve is slightly retarded in its opening movement so as to increase the efficiency of the internal combustion engine to which the carburetor is attached and by the particular construction the parts move freely without any danger of the air valve not working properly under all conditions. By the particular construction of piston and screw, a fluid dash pot is formed wherein the fluid within the tubular screw is displaced by the piston as the suction controlled valve is moved into open position and by varying the size of the vent or passage, the speed of movement of the piston can be determined so that the proper resistance will be obtained to retard the movement of the valve.

By providing a combination spring and fluid dash pot for the air valve of the carburetor, the cylinder of the dash pot is adjustably mounted in respect to the piston whereby the cubic contents of the cylinder can be varied and at the same time the tension of the spring can be increased or decreased so as to control the movement of the air valve to a nicety.

What I claim is:—

1. A carburetor having a mixing chamber provided with high and low speed nozzles, a pivoted suction controlled valve mounted in said mixing chamber over said high speed nozzle, said valve having a bifurcated stem on the upper face thereof, the wall of said mixing chamber being provided with a threaded bore, a tubular screw working in said bore, a piston slidably mounted in said tubular screw having an opening forming a passage for fluid on the movement of said piston, a spring disposed in said screw beyond said piston and a rod pivotally mounted in said bifurcated stem extending across said mixing chamber above said valve and having a pivotal connection with said piston.

2. A carburetor having a mixing chamber provided with a high and low speed nozzle, a pivoted suction controlled valve mounted in said mixing chamber over said high speed

nozzle, a tubular screw working in the wall of said mixing chamber, a piston slidably mounted in said tubular screw having an opening forming a passage for fluid on the movement of said piston, a rod pivotally connected to the top of said suction valve extending transversely across said mixing chamber having a pivotal connection with said piston and a spring disposed in said screw beyond said piston.

In testimony whereof I hereunto affix my signature.

JACOB RICHARD FRANCIS.
